PORTABLE TAPE RECORDER OR SIMILAR ARTICLE

Paul Belokin, Jr., Berwyn, Ill., assignor to Webcor, Inc.,
Chicago, Ill., a corporation of Illinois

Filed Dec. 4, 1963, Ser. No. 77,664

Term of patent 14 years

(Cl. D26—14)

FIG. 1

FIG. 2

FIG. 3

FIG. 4

FIG. 5

FIG. 6

FIG. 7

FIG. 8

FIGURE 1 is a front elevational view of a portable tape recorder or similar article showing my new design, with the cover in place;

FIG. 2 is an elevational view of the right side thereof; FIG. 3 is an elevational view of the left side thereof; FIG. 4 is a back elevational view thereof;

FIG. 5 is a top plan view thereof;

FIG. 6 is a bottom plan view thereof;

FIG. 7 is a front elevational view thereof with the cover removed; and

FIG. 8 is an elevational view of the right side thereof with the cover removed.

The drawing figures are stippled to indicate a leather grain contrast in appearance.

I claim.

The ornamental design for a portable tape recorder or similar article, as shown and described.
